INVENTOR

Peter Niewiarowski

BY
George E. Heinricke

ATTORNEY

UNITED STATES PATENT OFFICE.

PETER NIEWIAROWSKI, OF OMAHA, NEBRASKA, ASSIGNOR OF ONE-HALF TO JOHN DOMBROWSKI, OF OMAHA, NEBRASKA.

RAIL-JOINT.

1,362,957.

Specification of Letters Patent. Patented Dec. 21, 1920.

Application filed May 13, 1920. Serial No. 380,980.

To all whom it may concern:

Be it known that I, PETER NIEWIAROWSKI, a citizen of the United States, residing at Omaha, county of Douglas, and State of 5 Nebraska, have invented certain new and useful Improvements in Rail-Joints, of which the following is a specification.

The present invention relates to improvements in rail joints and it is the principal 10 object to provide a rail joint which produces a rigid connection between the ends of two adjoining rails while leaving enough play between these ends for compensation of the changes to which the rails are submitted under the changing temperatures.

A further object of the invention is to provide a rail joint which will reduce the so-called "pounding" of the car wheels when running over a rail joint to a minimum and 20 thus greatly adding to the comfort of the passengers and result in a great saving of material.

A still further object of the invention, is the provision of a rail joint allowing the 25 construction of a track presenting an almost uninterrupted appearance.

Furthermore, the rail joint of the present invention will positively prevent a displacement of two adjoining rails in longitudinal direction and thus relieve greatly 30 the stress on the fastening means.

Another object is to provide a rail which will allow a ready exchange of worn out rails. The above mentioned objects are attained in the construction illustrated and 35 fully described herein, which is simple, cheap and durable, as well as economical in use.

Referring to the drawing—

Figure 1 represents a top plan, and 40 Fig. 2 a side elevation of a rail construction substantially in conformity to my invention.

Fig. 3 represents side views of a rail joint according to the present invention.

Fig. 4 is a horizontal section through a rail, showing a connecting bolt in top plan view.

Fig. 5 is a top plan view of a modified form of rail connection, and

50 Fig. 6 is a side view thereof.

In practically carrying out my invention the track is composed of two rails 10 and 10 resting upon the customary ties 11. The ends of two adjoining rails 10 being interlocked as for instance shown at 12.

In order to allow the interlocking of the ends of two rails, each of these rails is formed at one end with a vertical longitudinal substantially V-shaped slot or groove extending from the head of the rail through the 60 web thereof and its foot flange. The inner apex of the V being enlarged to form a substantially circular opening 14.

The opposite end of each rail is reduced and presents a substantially V-shape part or 65 wedge 15 ending in an outer substantially circular head 16, said head and wedge part adapted to snugly fit into the opening 14 and V shaped groove 13 of the adjoining rail end respectively when both ends are 70 united by pushing, pressing or hammering the wedge shaped end of one rail from above into the groove at the end of the next adjoining rail.

In order to allow the passage of rail 75 securing bolts 17 through the wedge part 15 of one rail and the walls of the V-shaped groove in the end of the next adjoining rail said wedge part as well as the walls of the 80 grooves are provided with alining square holes 18'.

The securing bolts 17 are provided with heads 18 adapted to engage the web of a rail and shanks 19 and 19 separated by a V-shaped central slot 20 extending through 85 nearly the entire length of the bolt. On the opposite side of the web, the shanks 19 are each provided with a flange 21 and 21 gripping over the rail web on the side of the rail oppositely disposed to the head 18.

In order to securely fasten the bolt in 90 the holes 18' a wedge 22 is provided which may be driven into the V-shaped slot 20 between the elastic shanks of the bolts for spreading the same apart into intimate contact with the side walls of the square holes 18'.

In Fig. 5 a modified form of my invention is illustrated according to which the 100 ends of two adjoining rails 10' are dove-tailed as indicated at 11' one end adapted to fit into a suitably dove-tailed groove of the adjoining rail end, while bolt 17' of a similar construction as the bolt 17 serves to firmly unite the parts of the joint.

The construction and operation of the rail joint will be apparent from the foregoing description. It will however be understood that I do not desire to be limited to the present construction and arrangement shown or 110

described, it being clear that many changes may be made without departing from the spirit of the invention.

Having thus described my invention what I claim as new and desire to secure by Letters Patent of the United States is as follows—

For connecting the perforated ends of two adjoining rails of a rail joint of the character described, a bolt, a head on one end of said bolt adapted to engage a rail web on one side, two straight elastic shanks separated by a central V-shaped groove passed through the perforations of the rail ends,

flanges at the outer ends of said shanks adapted to engage the web of a rail opposite to the point of engagement with said head, and a wedge adapted to be driven with its sharp point between both shanks for bringing the same into contact with the walls of the rail perforations permitting of a convenient readjustment, substantially as described and for the purpose set forth.

In testimony whereof I have affixed my signature.

PETER NIEWIAROWSKI.

Witness:

J. E. KOPFERTZ.
